UNITED STATES PATENT OFFICE.

CHARLES A. STEVENS, OF NORRISTOWN, PENNSYLVANIA.

COIN-CONTROLLED HEIGHT-INDICATING MACHINE.

1,095,040.

Specification of Letters Patent. Patented Apr. 28, 1914.

Application filed September 10, 1912. Serial No. 719,679.

To all whom it may concern:

Be it known that I, CHARLES A. STEVENS, a citizen of the United States, residing at Norristown, in the county of Montgomery and State of Pennsylvania, have invented new and useful Improvements in Coin-Controlled Height-Indicating Machines, of which the following is a specification.

This invention relates to coin operated height indicating machines, the object in view being to provide a machine of the class described, embodying a graduated cylinder, the graduations of which are normally concealed, an indicator being adapted to travel across the graduated face of the cylinder, and in connection therewith to display the correct measurement of the person operating the machine, together with a single operating element, by means of which the cylinder is turned, so as to display the graduated face thereof, and the indicator simultaneously moved across the face of the cylinder, the machine as a whole being normally locked but capable of operation only when a coin is inserted therein.

With the above and other objects in view, the invention consists in the construction, combination and arrangement of parts, as will be hereinafter more fully described, illustrated in the accompanying drawings, and pointed out in the claims hereunto appended.

In the drawings: Figure 1 is a front elevation of a machine, embodying the present invention. Fig. 2 is a vertical cross section of the same, taken on the line 2—2 of Fig. 1. Fig. 3 is a horizontal section on the line 3—3 of Fig. 1. Fig. 4 is a rear elevation of the machine with the back wall removed. Fig. 5 is a vertical section illustrative of the several steps of the follower and coin mechanism. Fig. 6 is a detail vertical section taken centrally of the upper forward portion of the machine, showing the folding contact arm and the operating means therefor.

The height indicating machine contemplated in this invention comprises a suitable stand 1 in the form of a box-like casting, in which the operative parts of the mechanism are mounted, 2 designating the floor or surface upon which the operator stands, preparatory to manipulating the machine to ascertain his height.

The front of the stand is provided with an

observation opening 3, directly behind which is arranged a vertical cylinder 4 which is, therefore, adapted to be displayed through the opening 3. This cylinder is journaled on a vertical axis, by means of bearings 5 and 6 at the top and bottom thereof, said bearings being supported by horizontal cross bars 7 and 8, respectively, said cross bars being rigidly attached to the stand and concealed within the same.

The cylinder is provided with graduations, as shown at 9, for the purpose of indicating the height of the operator, the cylinder being normally held in the position illustrated in Figs. 1 and 2, so that the graduations are concealed, while any suitable printed matter may be represented on the exposed portion of the cylinder, as indicated in Fig. 1, in which a panel 10 is shown adapted to contain certain directions for manipulating the machine.

The front wall of the stand is provided with a vertical slot 11 at one side, extending parallel to the observation opening 3, as shown in Fig. 1, and mounted to move longitudinally of the slot 11 is a slide 12 having secured to the forward face thereof a face plate 13 provided with an operating knob 14, by means of which the slide 12 may be moved up and down in the slot 11.

Extending from the upper portion of the slide 12 toward the center of the machine is an indicator carrying arm 15, to which an indicator 16 is attached, the same being in the form of a plate, as shown, the bottom edge of which is adapted to register with the proper graduation of the cylinder for indicating the exact height of the operator.

Pivottally mounted on the indicator is a contact arm 17 which, in the operation of the machine, is moved downwardly until it rests upon the head of the operator. This arm 17 is provided with a T-shaped base 18 journaled in suitable eyes or bearings 19 on the indicator plate 16, while the end portions of the base 18 are bent at right angles to form fingers 20 adapted to come into contact with fixed projections 21, shown by preference as extending forward from the upper cross bar 7, hereinabove referred to, the object in view being to cause the contact arm 17 to fold upward, as the slide indicator 16 moves in the corresponding direction, thereby moving the contact arm from the

horizontal position, shown in Fig. 6, to the vertical or folded position, illustrated in Figs. 1 and 2.

Referring now to Fig. 4, 22 designates a lever pivoted to a fixed point, as shown at 5 23, and arranged in the path of the downwardly moving slide 12. Connected to the free end of the lever 23 is a cord or flexible element 24 which passes over a guide pulley 25, near the top of the machine, and thence downwardly around another guide pulley 26 and across to the cylinder, to which it is connected, as shown at 27, the connection being illustrated in the form of a pin projecting 10 from the face of the cylinder, to which the cord 24 is attached. After fastening the cord to the cylinder, it is extended over another pulley 28, and thence downward, where it is attached to a weight 29 which 15 serves to restore the cylinder to its normal non-indicating position. It will now be observed that when the slide 12 is depressed, it comes into contact with the lever 22, and operates the cord 24, causing the latter to 20 give a partial rotative movement to the cylinder 4, so as to bring the graduated face thereof into view through the observation opening 3.

A slide controlling weight 30 is arranged 30 in a suitable box 31 within the stand, and is connected by a cord 32 to the slide 12, said cord passing over guide pulleys 33 near the top of the machine. After the measurement is obtained and the knob 14 is released, the 35 weight 30 serves to return the slide to its initial position.

The coin-controlled part of the mechanism embodies a coin chute 34 extending vertically within the stand and provided 40 in the rear face thereof with a slot 35 adapted to receive an L-shaped arm 36 extending from and rigidly connected to the slide 12 and movable therewith in a vertical direction. Secured rigidly to the arm 36 is 45 a coin follower 37, the bottom edge or face of which is concaved, as shown at 38, to fit a coin of the proper denomination, such coin being shown at 39. Near the top of the coin chute 34 and within the same are oppositely 50 arranged curved spring fingers 40, the convex surfaces of which are disposed toward each other, as best illustrated in Fig. 5, and the upper extremities of which are arranged at a less distance apart than the width of 55 the follower 37, so that it is impossible to force the follower 37 down into the coin chute, as it will come into contact with the spring fingers 40, the latter forming a positive stop therefor. When, however, a coin 60 is inserted through a coin slot 41 in the front of the stand, as shown in Figs. 1 and 2, said coin will lodge upon the upper extremities of the spring fingers 40 and then, when the follower 37 is depressed by operating the 65 slide 12, the coin will wedge in between and

spread apart the spring fingers 40, thereby allowing the follower 37 to force its way also between the fingers 40, which will permit the slide 12 to be moved downward by depressing the knob 14. As soon as the coin 39 70 passes below the spring fingers 40, it is released and falls by gravity into a coin receptacle 42 within the stand.

In operation, the person desiring to ascertain his correct height stands upon the floor 75 or platform 2. He then places a coin in the slot 41 and grasps the knob 14 and moves the latter downward. In this movement, the slide 12 is forced downward and by means of the cord 24 the cylinder 4 is partially 80 turned on its vertical axis, so as to display the graduated face thereof. Simultaneously therewith, the indicator 16 is moved downward across the graduated face of the cylinder, and the contact arm 17 drops from its 85 vertical folded position to its operative horizontal position. The downward movement of the knob 14 is continued until the contact arm 17 rests upon the head of the operator, who, by then looking at the bottom edge of 90 the indicator 16, may read his indicated height on the graduated surface of the cylinder. Upon releasing the knob 14, the parts are returned to their initial positions by means of the counterbalancing weight 29 95 and 30, and at the same time the follower passes above the spring fingers 40, thus locking the machine until another coin is inserted therein.

What is claimed is:

1. A coin-controlled height indicating machine, comprising a stand having an observation opening, a cylinder provided with a graduated scale and mounted to turn on a vertical axis on said stand and so related to the stand as to show the graduated scale through said observation opening when turned in one direction and conceal the scale when turned in the opposite direction, an indicator movable lengthwise of said cylinder, a contact arm carried by said indicator, and means for turning the cylinder, and also moving said indicator and contact arm. 100

2. A coin-controlled height indicating machine, comprising a stand, a graduated cylinder mounted to turn on a vertical axis on said stand, an indicator movable lengthwise of said cylinder, a contact arm movable with the indicator, and means for turning the cylinder and also moving said indicator. 105

3. A coin-controlled height indicating machine, comprising a stand, a graduated cylinder mounted to turn on a vertical axis on said stand, an indicator movable lengthwise of said cylinder, a contact arm pivotally connected to and movable with the indicator, and means for turning the cylinder and also moving said indicator. 110

4. A coin-controlled height indicating machine, comprising a stand, a graduated cyl- 115

120

130

inder mounted to turn on a vertical axis on said stand, an indicator movable lengthwise of said cylinder, a contact arm carried by said indicator, and a manually operated slide 5 for turning the cylinder and moving said indicator.

5. A coin-controlled height indicating machine, comprising a stand, a graduated cylinder mounted to turn on a vertical axis on 10 said stand, an indicator movable lengthwise of said cylinder, a contact arm carried by said indicator, manually operated means for turning the cylinder and also moving said indicator, and means for automatically re- 15 storing the cylinder and indicator to their initial positions.

6. A coin-controlled height indicating machine, comprising a stand, a graduated cylinder mounted to turn on a vertical axis on 20 said stand, an indicator movable lengthwise of said cylinder, a contact arm carried by said indicator, manually operated means for turning the cylinder and also moving said indicator along the graduated surface of the 25 cylinder, and overbalancing means for restoring said cylinder and indicator to their initial positions.

7. A coin-controlled height indicating machine, comprising a stand, a graduated cylinder mounted to turn on a vertical axis on 30 said stand, an indicator movable lengthwise of said cylinder, a contact arm carried by said indicator, and means for turning the

cylinder and also moving said indicator, embodying a slide, and means for releasably 35 locking said slide.

8. A coin-controlled height indicating machine, comprising a stand, a graduated cylinder mounted to turn on a vertical axis on 40 said stand, an indicator movable lengthwise of said cylinder, a contact arm carried by said indicator, and means for turning the cylinder and also moving said indicator, embodying a slide, an arm connecting the slide 45 with the indicator, and a flexible element connecting the slide with the cylinder.

9. A coin-controlled height indicating machine, comprising a stand having an observation opening, a cylinder provided with a graduated scale and mounted to turn on a 50 vertical axis on said stand and arranged with reference to the stand and observation opening to show the graduated scale when turned in one direction and to conceal the scale when turned in the opposite direction, 55 an indicator movable lengthwise of said cylinder, a contact arm carried by said indicator, and means for turning the cylinder and also moving said indicator.

In testimony whereof I affix my signature 60 in presence of two witnesses.

CHARLES A. STEVENS.
